CONCRETE SPREADER

John P. Faber, Dunellen, N. J., assignor to Ransome Machinery Company, Dunellen, N. J., a corporation of New Jersey

Application September 28, 1944, Serial No. 556,128

20 Claims. (Cl. 94—45)

1

This invention relates to apparatus for spreading concrete which has been deposited upon a roadway or the like, as from the usual concrete mixing apparatus, to supplant the difficult and costly manual work involved in conventional methods of distributing, spreading and leveling the concrete.

Conventional types of concrete paving machines or mixers employ a boom of considerable length which is supported by cables from the frame of the machine in which the mixing drum is mounted. This boom provides a track on which the distributing bucket runs to and from the mixer to receive and convey to points distant from the mixer the mixed concrete and dump it at convenient points, after which the concrete is spread and formed into a pavement by workmen.

The boom is pivotally mounted on the frame of the machine adjacent the discharge spout of the mixer so that it can be swung laterally to bring its outer part and the bucket thereon to different points from side to side of the road grade being paved, and the bucket is provided with means for propelling it along the boom in both directions and for tripping its bottom door at any desired point along the boom for depositing its load of mixed concrete at that point.

The tendency in recent times is to increase the capacity of the mixing drum, so that large batches of concrete can be mixed therein and discharged therefrom and the work thus expedited. Efficient and economical operation of the mixer also requires that the full batch of the drum shall be discharged therefrom in one operation, so that it can be immediately recharged, and the mixing carried on while the concrete is being distributed. The use of such large capacity mixing drums makes the problem of distribution of the concrete on the roadway all the more important, notwithstanding the fact that the bucket may be discharged at any desired point within the range of the boom.

The fact that the buckets can be dumped at any point along the boom affords only a partial solution with respect to distribution of the concrete on the roadway and the formation of the concrete into a pavement. A bucket which dumps its entire contents at one point requires that the greater part of this load of concrete be spread and distributed by hand or that only a part of the batch of concrete mixed and ready for distribution be discharged into the bucket and distributed, which greatly reduces the normal output of the machine and results in serious

2

loss to the contractor. To overcome this objection, double buckets have been employed.

In the dual bucket type of apparatus, the buckets are arranged to be operated independently in association with two boom sections secured together and operating as a single boom. The buckets are loaded by being presented together at the discharge spout of the mixer, and the batch of concrete is divided evenly between them as it comes from the discharge spout. One of the buckets may be drawn out on the boom and discharged or both buckets may be discharged at the same time, and at the same or different points along the boom.

10 When the buckets in the dual type of apparatus are moved to the dumping point and discharged separately, the boom may be swung laterally after one bucket is discharged and before the other is moved to a discharging point so that the batch may be deposited on the grade at two points spaced from each other longitudinally or laterally, or in both directions, and a part of the manual work of spreading and placing the batch thus dispensed with. While the dual type of apparatus operates efficiently so far as division of the batch and mixing production of the drum are concerned, this type, as well as other types of mixers still requires that the concrete be spread over a considerable area, which involves a great deal of manual labor in spreading and placing it properly on the grade.

Accordingly, an object of the present invention is to provide an apparatus embodying novel means for expeditiously spreading concrete deposited upon a supporting surface.

Another object is to provide a concrete spreader for distributing concrete deposited upon a roadway, in which a novel concrete spreading unit is employed, and in which novel means are incorporated for moving the spreading unit in a horizontal path over the roadway.

45 A further object is to provide a concrete spreader apparatus adapted to move along form members such as are employed in pavement construction work, to be guided thereby both as to the direction of progression of the work and vertically with respect to the roadway surface, in which a novel rotary spreading means are provided for distributing concrete deposited upon the roadway between the form members, and in which novel means are provided for propelling the rotary spreading means back and forth across the roadway and simultaneously rotating the spreading means.

55 With these and other objects in view, as may

appear from the accompanying specifications, the invention consists of various features of construction and combination of parts, which will be first described in connection with the accompanying drawings, showing a concrete spreader of a preferred form embodying the invention, and the features forming the invention will be specifically pointed out in the claims.

In the drawings:

Figure 1 is a top plan view of a concrete spreader in accordance with the present invention, with a portion broken away for the sake of conciseness.

Figure 2 is a front elevational view of the structure of Figure 1.

Figure 3 is an end elevational view of the concrete spreader, a portion thereof being removed for the sake of illustration.

Figure 4 is a view taken from the position indicated by line 4—4 of Figure 3.

Figure 5 is a view taken along the line 5—5 of Figure 3.

Figure 6 is a partial sectional view of a concrete spreading unit adjusting device.

Figure 7 is a sectional view taken along the line 7—7 of Figure 6.

Figure 8 is a view taken from the position indicated by line 8—8 of Figure 2.

Referring more particularly to the drawings, Figures 1, 2, and 3 illustrate a carriage or support 10 which is provided with flanged traction wheels 11 arranged to run on spaced parallel form members 12 such as are used in concrete pavement construction work for defining the side limits of the pavement. The carriage 10 comprises in part two hollow frame members 13, each of which defines one side of the carriage. Each member 13 is mounted upon two legs 14, and each leg is supported by one of the traction wheels 11. The wheels 11 are attached to shafts or axles 15 which are supported in bearings 16 mounted on the respective legs.

Means for driving the traction wheels 11 include a horizontal shaft 17 which extends the full width of the carriage 10 directly above the axles 15 of the two rear wheels 11. The shaft 17 is supported in bearings 18 attached to the two frame members 13, and the shaft is provided with sprockets 19 for driving chains 20 passing around sprockets 21 attached to the two rear axles 15. To the shaft 17 and within the two frame members 13 are attached two sprockets 22 for driving chains 23 each extending horizontally inside one of the frame members toward the forward end of the carriage. Each chain 23 passes around a sprocket 24 attached to a shaft 25, the latter being supported in bearings 26 mounted inside the respective frame member 13. A sprocket 27 is attached to each shaft 25 for driving a chain 28 which passes around a sprocket 29 attached to one of the front axles 15.

The sprockets 21 and 29 are of the same diameter, and the sprockets 19, 22, 24, and 27 are also of the same diameter so that all the traction wheels 11 will be driven at the same speed. Power for driving the shaft 17 is supplied by an engine or motor 30 which is mounted on the carriage 10. A speed reducer 31, of any approved type, is connected with the engine 30 as at 32, and is provided with power take-off sprockets 33 and 34. A chain 35 passes around the sprocket 33 and a second sprocket 36 attached to the shaft 17 for driving the latter. Speed reducers of the foregoing type, including controls for controlling the transmission of power through the two sprockets

33 and 34, are old and well known in the art and need not be described in further detail.

Means for distributing, spreading, and leveling concrete deposited upon the roadway or other supporting surface comprises a spreader or spreading unit 37. The spreader 37 is mounted on a traveler or carriage 38 which is arranged for movement back and forth along a track or guide 39, the latter extending crosswise of the carriage 10; that is, at right angles to the form members 12. The track 39 comprises two parallel but spaced I-beams 40 which are mounted on the frame members 13. The traveler 38 comprises a yoke 41 which underlies the I-beams 40 and which is provided with two upstanding walls 42, each of which is provided with two flanged wheels 43 arranged to run on the bottom flange 44 of one of the I-beams 40, with the two I-beams located between the two sets of wheels.

Back and forth movement is imparted to the traveler 38 by an endless chain 45 which passes around a drive sprocket 46 and an idler sprocket 47 rotatably mounted on one of the I-beams 40, with the sprockets so arranged as to place the straight reaches of the chain (disregarding slack) in parallelism with the flange 44 of the I-beam. An arm 48 is fixed to the yoke 41 and has a pivotal connection 49 with an arm 50 attached to one link of the chain 45. The arm 50 extends inwardly of the chain, and the pivotal connection 49 is located with its axis coincident with a straight line passing through the axes of the drive sprocket 46 and the idler sprocket 47.

It will thus be seen that as the arm 50 is carried by the lower reach of the chain 45, the traveler 38 will be moved in the same direction and that when the arm is carried by the upper reach of the chain, the traveler will be moved in a reverse direction; also that the traveler 38 remains stationary while the arm 50 moves through the curved phases of the chain 45 in its passage around the two sprockets 46 and 47. Accordingly, unidirectional movement of the chain 45 is translated into back and forth movement of the traveler 38, which moves the spreader 37 back and forth in a horizontal path across the roadway or other surface being paved.

The spreader 37 comprises a plurality of identical blades 51 which are fixed to a hub 52, the latter being attached to a vertical shaft 53 which is carried by the traveler 38. The blades 51 radiate from the axis of the shaft 53 and are equally spaced one from the other circumferentially of the shaft. According to Figure 8, each blade is provided with two vertical side faces 54 which terminate in a vertical outer edge 55, and the faces 54 are of such angular relationship with respect to each other and curvature as to define a blade body of increasing thickness from the hub 54 throughout substantially half the radial length of the blade, with the thickness decreasing from that point outwardly to the vertical edge 55.

In addition to the back and forth movement of the spreader 37 in a horizontal path, the spreader is caused to rotate about the axis of the shaft 53 throughout the horizontal travel of the spreader in either direction, which provides a blade action which effectively distributes the concrete engaged by the blades 51. To that end, the shaft 53 is rotatably supported in a tubular bearing 56 which is attached to the yoke 41. Upon the shaft 53 is mounted a gear 57 which has a key 58 slidably confined in a longitudinal groove 59 in the shaft to impart rotation to the shaft 53 when the gear is rotated, but with the shaft free

to shift axially of the gear to permit adjustment of the spreader 37 in a vertical direction.

Since the gear 57 is mounted on the shaft 53, this gear travels back and forth with the traveler 38, and the gear meshes with a rack 60 fixed to the I-beam 48 opposite the chain 45, so that the gear 57 is caused to roll along the rack through back and forth movement of the traveler 38. When viewing Figure 1, movement of the traveler 38 from right to left causes counterclockwise rotation of the shaft 53 and its attached spreader 37, while movement of the traveler from left to right causes clockwise rotation of the shaft and the traveler.

In view of the fact that the carriage 10 may be moved along the form members 12 and that the traveler 38 travels back and forth along the track 39 which is arranged at right angles to the form members 12, the spreader 37 is capable of universal movement or positioning in a horizontal plane. Such positional adaptability of the spreader 37 together with its power driven spreading blades, provides an apparatus which effectively distributes concrete deposited in large or small batches upon the roadway or other supporting surface.

The sprocket 46, which drives the chain 45, is fixed to a rotary shaft 61 which is provided with a second sprocket 62. A chain 63 connects the sprocket 62 with the power take-off sprocket 34.

In Figure 6, the shaft 53 extends some distance above the gear 57 and is threaded at 64 for threaded connection with a hub or nut 65 of a handwheel 66. The hub 65 rests on the gear 57, with the gear resting on the upper end of the tubular bearing 56. It will thus be seen that the shaft 53 may be adjusted vertically through rotation of the handwheel 63. A shoulder 67 is provided on the shaft 53 for engagement with the gear 57 to prevent the rotary blades 51 from being lowered beyond their maximum depth.

Between the rear wheels 11 and the spreader 37 is mounted a strike-off blade 68 which extends at right angles to the frame members 13 and is employed for contouring the finished surface of the pavement after general distribution of the concrete by the spreader 37. The strike-off blade 68 is made in sections 69 which are arranged end to end and flatwise against a supporting angle 70. Slots 71 are provided in the sections 69 for the reception of bolts 72 which are threaded into or through the angle 70. Thus the individual sections 69 may be adjusted vertically to modify the contour forming characteristics of the strike-off blade.

The angle 70 is attached to the lower flange of an I-beam 73, and angles 74 are attached to the I-beam for engagement with the two rear legs 14 to guide the I-beam when it is raised and lowered, as when the strike-off blade is adjusted vertically in accordance with specific road building requirements, or for moving purposes. Means for raising and lowering the I-beam 73 comprise plunger rods 75 which are attached to the I-beam and operated by hydraulic cylinders 76 mounted on the two frame members 13. Carriage supported strike-off blades and hydraulic cylinder controlling means therefor are old and well known in the art and need not be described in more detail.

It will be understood that the invention is not to be limited to the specific construction or arrangement of parts shown, but that they may be widely modified within the invention defined by the claims.

What is claimed is:

1. A concrete spreader for distributing concrete deposited upon a supporting surface comprising a support, a horizontal track carried by said support, a carriage movable along said track, a bladed concrete spreading unit mounted on said carriage for rotation about a vertical axis, means for propelling said carriage back and forth along said track to move said spreading unit in a horizontal path over the supporting surface, and means for rotating said spreading unit, said bladed concrete spreading unit having blades each provided with curved concrete spreading faces.

15 2. A concrete spreader for distributing concrete deposited upon a supporting surface comprising a support, a horizontal track carried by said support, a carriage movable along said track, a bladed concrete spreading unit mounted on said carriage for rotation about a vertical axis, means for propelling said carriage back and forth along said track to move said spreading unit in a horizontal path over the supporting surface, and means for rotating said spreading unit in one direction during movement of said carriage in one direction along the track and in the reverse direction upon reverse movement of the carriage along the track, said bladed concrete spreading unit having blades each provided with curved concrete spreading faces.

25 3. A concrete spreader for distributing concrete deposited upon a supporting surface comprising a support, a horizontal track carried by said support, a carriage movable along said track, a concrete spreading unit mounted for rotation on said carriage, means for propelling said carriage back and forth along said track to move said spreading unit in a horizontal path over the supporting surface, a rack extending along said track, and a gear operatively connected with said spreading unit and meshing with said rack for imparting rotary motion to the spreading unit through movement of said carriage along said track, said concrete spreading unit having vertically positioned blades each provided with concrete spreading faces reversely curved with respect to each other.

40 4. A concrete spreader for distributing concrete deposited upon a supporting surface comprising a support, a horizontal track carried by said support, a carriage movable along said track, a concrete spreading unit mounted on said carriage for rotation about a vertical axis, means for propelling said carriage back and forth along said track to move said spreading unit in a horizontal path over the supporting surface, a rack fixed to and extending along said track, a gear operatively connected with said spreading unit and meshing with said rack for imparting rotary motion to the spreading unit through movement of said carriage along said track, and means for adjusting said spreading unit vertically, said concrete spreading unit having vertically positioned blades each provided with concrete spreading faces reversely curved with respect to each other.

45 5. In a concrete spreader for distributing concrete on a surface to be concreted, a carriage adapted to be supported on and moved along spaced parallel form members, horizontal guide means carried by said carriage crosswise of the form members, a traveler movable along said guide means, a bladed concrete spreading unit mounted on said traveler for rotation about a vertical axis, an endless chain, a drive sprocket and an idler sprocket for driving the chain and supporting the latter in parallelism with said guide means, an operating connection between

said chain and said traveler, said operating connection having a pivotal connection with said traveler at a point coincident with a straight line passing through the axes of said drive sprocket and the idler sprocket for propelling the traveler and said spreading unit back and forth along said guide means through unidirectional movement of said chain, a rack fixedly related to said guide means, a gear operatively connected with said spreading unit and meshing with said rack for rotating the spreading unit through movement of the traveler along said guide means, and means for adjusting said spreading unit vertically.

6. In a concrete spreader for distributing concrete on a surface to be concreted, a carriage adapted to be supported on and moved along spaced parallel form members, horizontal guide means carried by said carriage crosswise of the form members, a traveler movable along said guide means, a bladed concrete spreading unit mounted on said traveler for rotation about a vertical axis, an endless chain, a drive sprocket and an idler sprocket for driving the chain and supporting the latter in parallelism with said guide means, an operating connection between said chain and said traveler, said operating connection having a pivotal connection with said traveler at a point coincident with a straight line passing through the axes of said drive sprocket and the idler sprocket for propelling the traveler and said spreading unit back and forth along said guide means through unidirectional movement of said chain, a rack fixedly related to said guide means, a gear operatively connected with said spreading unit and meshing with said rack for rotating the spreading unit through movement of the traveler along said guide means, means for adjusting said spreading unit vertically, a power means drivingly connected with said drive sprocket, traction wheels on said carriage engaging the form members, and a driving connection between said traction wheels and said power means for moving the carriage along the form members.

7. A concrete spreader for distributing concrete deposited upon a supporting surface comprising a support, a horizontal track carried by said support, a traveler movable along said track, a bladed concrete spreading member having a vertical shaft rotatably mounted on said traveler, a rack extending along said track and fixedly related thereto, a gear mounted on said shaft and meshing with said rack, said shaft being keyed to said gear for rotation therewith but movable axially relatively to the gear, means for restraining the gear from shifting laterally of the rack, means for adjusting the shaft axially to shift said concrete spreading member relatively to the supporting surface, and means for moving said traveler back and forth along said track to impart corresponding movement to the concrete spreading member and to cause said gear to roll along said rack for rotating said concrete spreading member.

8. A concrete pavement building apparatus comprising a carriage, a rotative concrete spreading means for distributing concrete deposited upon a roadway, a guide extending crosswise of the roadway and mounted on said carriage, a traveler movable along said guide, said concrete spreading means including an upright shaft and a bearing on said traveler for rotatively supporting the shaft, a rack fixedly related to said carriage, a gear splined to said shaft and meshing

with said rack to impart rotation to the concrete spreading means when said traveler is moved along said guide, a hand wheel having a hub threadedly connected with said shaft, said gear being located between said bearing and said hub, said hub resting on said gear to support the weight of said concrete spreading means and for adjusting the latter for height through rotation of the hand wheel, and means for propelling said traveler back and forth along said guide.

9. A concrete spreader for distributing concrete deposited upon a surface including a movable supporting carriage, a traveler means for moving said traveler transversely of the direction of movement of the carriage, concrete spreading means carried by said traveler, said spreading means comprising a plurality of radiating blades having convex concrete engaging surfaces, and means for rotating said spreading means about a vertical axis during movement of the traveler across said carriage.

10. In a concrete spreader for distributing concrete deposited upon a surface the combination with a movable supporting carriage, a traveler carried by said carriage means for moving said traveler transversely of the direction of movement of the carriage, concrete spreading means carried by said traveler, said spreading means comprising a plurality of radiating blades having convex concrete engaging surfaces, means embodying a gear for rotating said spreader about a vertical axis during movement of the traveler across the carriage and means co-operating with said gear for adjusting said spreading means vertically relative to said traveler.

11. A concrete spreader for distributing concrete deposited upon a surface including a movable supporting carriage, a track extending transversely across said carriage, a traveler movable along said track, means for moving said traveler along said track, concrete spreading means carried by said traveler and including a plurality of radiating convex concrete engaging surfaces, and means connected to said spreading means and said track for rotating the spreading means as the traveler moves along the track.

12. A concrete spreader for distributing concrete deposited upon a surface including a movable supporting carriage, a track extending transversely across said carriage, a traveler movable along said track, means for moving said traveler along said track, concrete spreading means carried by said traveler and including a plurality of radiating convex concrete engaging surfaces, a vertical shaft connected to said spreading means, a gear feathered to said shaft for rotation with the shaft and to permit longitudinal movement of the shaft relative to the gear, and means carried by said track for engagement with said gear to rotate said spreading means as said traveler moves along said track.

13. A concrete spreader for distributing concrete deposited upon a surface including a movable supporting carriage, a track extending transversely across said carriage, a traveler movable along said track, means for moving said traveler along said track, concrete spreading means carried by said traveler and including a plurality of radiating convex concrete engaging surfaces, a vertical shaft connected to said spreading means, a gear feathered to said shaft for rotation with the shaft and to permit longitudinal movement of the shaft relative to the gear, means co-operating with said gear and shaft to move said spreading means vertically, and

means carried by said track for engagement with said gear to rotate said spreading means as said traveler moves along said track.

14. In apparatus for spreading concrete deposited upon a road bed, a main frame traversable longitudinally along said bed, said frame having a transverse trackway; a wheeled carriage mounted on said trackway; power operated means for reciprocating said carriage upon the trackway; a spreading blade mounted by the carriage for movement relative thereto about a vertical axis; and mechanism for so moving the blade throughout traverse of the carriage on the trackway.

15. In apparatus for spreading concrete deposited upon a road bed, a main frame traversable longitudinally along said bed, said frame having a traverse trackway, a wheeled carriage mounted on said trackway, power operated means for reciprocating said carriage upon the trackway; a spreading blade mounted on the carriage for movement relative thereto about a vertical axis, mechanism for so moving the blade throughout traverse of the carriage on the trackway, and mechanism for adjusting said spreading blade vertically without affecting movement of the blade about its vertical axis.

16. In apparatus for spreading concrete deposited upon a road bed, a main frame traversable longitudinally along said bed, said frame having a traverse trackway, a wheeled carriage mounted on said trackway, power operated means for reciprocating said carriage upon the trackway, a spreading blade mounted by the carriage for movement relative thereto about a vertical axis, a vertical shaft connected to said spreading blade, a gear feathered to said shaft to permit longitudinal movement of the shaft relative to the gear, means connected to said gear for moving the spreading blade on a vertical axis and relative to the carriage throughout traverse of the carriage on the trackway, and mechanism connected to the shaft for moving the shaft and spreading blade vertically relative to said gear.

17. In apparatus for spreading concrete deposited upon a road bed, a main frame traversable longitudinally along said bed, said frame having a traverse trackway, a wheeled carriage mounted on said trackway, power operated means for reciprocating said carriage upon the trackway, a spreading blade mounted by the carriage for movement relative thereto about a vertical axis, mechanism for so moving the blade throughout traverse of the carriage on the trackway, said spreading blade comprising a plurality of individual blades radiating from a common center.

18. In apparatus for spreading concrete deposited upon a road bed, a main frame traversable longitudinally along said bed, said frame

having a traverse trackway, a wheeled carriage mounted on said trackway, power operated means for reciprocating the carriage upon the trackway, a spreading blade mounted by the carriage for movement relative thereto about a vertical axis, mechanism for so moving the blade throughout traverse of the carriage on the trackway, said spreading blade comprising a plurality of individual blades radiating from a common center, each of said individual blades having opposed curved surfaces for contact with concrete to be spread.

19. In apparatus for spreading concrete deposited upon a road bed, a main frame traversable longitudinally along said bed, said frame having a traverse trackway, a wheeled carriage mounted on said trackway, power operated means for reciprocating the carriage upon the trackway, a spreading blade mounted by the carriage for movement relative thereto about a vertical axis, mechanism for so moving the blade throughout traverse of the carriage on the trackway, and mechanism for adjusting said spreading blade vertically without affecting movement of the blade about its vertical axis, said spreading blade comprising a plurality of individual blades radiating from a common center.

20. In apparatus for spreading concrete deposited upon a road bed, a main frame traversable longitudinally along said bed, said frame having a traverse trackway, a wheeled carriage mounted on said trackway, power operated means for reciprocating the carriage upon the trackway, a spreading blade mounted by the carriage for movement relative thereto about a vertical axis, a vertical shaft connected to said spreading blade, a gear feathered to said shaft to permit longitudinal movement of the shaft relative to the gear, means connected to said gear for moving the spreading blade on a vertical axis throughout the traverse of the carriage on the trackway, said shaft having a portion of its length threaded, a nut on said threaded portion for moving the shaft and spreader blade vertically relative to said gear.
